Primary Examiner — Abraham Bahta(74) *Attorney, Agent, or Firm* — McDonald Hopkins LLC(57) **CLAIM**

The ornamental design for a label sheet assembly, as shown and described.

DESCRIPTION

FIG. 1 is a perspective view of the label sheet assembly showing my new design;

FIG. 2 is a front view of FIG. 1 thereof;

FIG. 3 is a back view of FIG. 1 thereof;

FIG. 4 is a first side view of FIG. 1 thereof;

FIG. 5 is a second side view of FIG. 1 thereof;

FIG. 6 is a top view of FIG. 1 thereof; and,

FIG. 7 is a bottom view of FIG. 1 thereof.

The broken lines in the figures are included for the purpose of illustrating portions of a label sheet assembly and form no part of the claimed design.

1 Claim, 4 Drawing Sheets# US D853,480 S
